UNITED STATES PATENT OFFICE

118,271

DESIGN FOR A DOUGH DIVIDER

Harold Van Doren and John McLeod Little, Toledo, Ohio, assignors to Baker Perkins Inc., Saginaw, Mich., a corporation of New York

Application July 3, 1939, Serial No. 85,841

Term of patent 14 years

To all whom it may concern:

Be it known that we, Harold Van Doren and John McLeod Little, citizens of the United States, both residing at Toledo, Lucas County, State of Ohio, have invented a new, original, and ornamental Design for a Dough Divider, of which the following is a specification, reference being had to the accompanying drawing, forming a part thereof.

Fig. 1 is a front perspective view of a dough divider, showing our new design.

Fig. 2 is a top plan view of the same.

Fig. 3 is a rear view thereof.

We claim:

The ornamental design for a dough divider, as shown.

HAROLD VAN DOREN.
JOHN MCLEOD LITTLE.
